[57] CLAIM

The ornamental design for a console for a telephone system, as shown and described.

DESCRIPTION

FIG. 1 is a front, top and right side perspective view of a console for a telephone system showing our new design;

FIG. 2 is a top plan view thereof;

FIG. 3 and 4 are respectively front and rear elevational views thereof;

FIG. 5 and 6 are respectively right and left side elevational views thereof;

FIG. 7 is a bottom plan view thereof;

FIG. 8 is a front, top and right side perspective view thereof with the bottom element in an alternate position; FIG. 9 is an elevational view thereof taken from the left of FIG. 8;

FIG. 10 is a bottom perspective view of the console as shown in FIG. 8; and

FIG. 11 is a top plan view of a second embodiment of the console having an alternative button pattern. The second embodiment of the console shown in FIG. 11 is identical to the first embodiment except for the alternate button pattern.
